AIR FLOW METER OR THE LIKE

Daniel O. Noorlander, Chino, Calif., assignor to Dairy Equipment Company, Madison, Wis., a corporation of Wisconsin

Filed Sept. 18, 1961, Ser. No. 66,733

Term of patent 14 years

(Cl. D52—6)

FIG. 1.

FIG. 2.

FIG. 3.

FIG. 5.

FIG. 4.

FIG. 6.

FIG. 1 is a front elevational view of an air flow meter showing my new design;

FIG. 2 is a rear elevational view thereof;

FIG. 3 is a side elevational view thereof taken from the left side as seen in FIG. 1;

FIG. 4 is a top plan view thereof;

FIG. 5 is a bottom plan view thereof; and

FIG. 6 is a sectional view taken along the arrows VI—VI of FIG. 1.

The dominant features of my design reside in the portions shown in full lines.

I claim:

The ornamental design for an air flow meter or the like, substantially as shown and described,
